N. J., a corporation of New Jersey

Application December 14, 1940, Serial No. 370,143

13 Claims.

(CL. 274—9)

This invention relates to phonographs and more particularly to commercial phonographs of the disk-record type.

The common or more conventional form of disk-record phonograph operates at constant rotational speed of the record and at a constant travelling speed of the translating device across the record. This mode of operation causes the linear speed of the record groove past the engaging stylus of the translating device to gradually diminish as the stylus moves through succeeding groove convolutions towards the center of the record. Two particularly undesirable results of this varying groove speed are that it introduces limitations in the quality which can be attained in the recording and reproducing operations and that, in the attainment of any given standard of quality for the record as a whole, it causes an unnecessary reduction in the playing time of the record.

To overcome these undesirable results, phonographs have been constructed to operate at a constant linear groove speed. This is achieved by progressively varying the rotational speed of the record as the translating device traverses the same and, in turn, by progressively varying the travelling speed between the translating device and the record in accordance with the record rotational speed.

The present invention is concerned with a "constant linear groove speed" type of phonograph wherein the varying speed of rotation of the record support or turntable is effected by means of a variable ratio friction drive, and wherein the varying speed of travel between the record and the translating device—the travel itself being in the present instance produced by holding the turntable axially stationary and moving the carriage for the translating device in translation relative thereto—is effected by a feed screw driven by the friction drive as for example from the turntable.

It is an object of my invention to provide a generally improved form of, and improvements in, a disk-record phonograph of the type here concerned.

A more particular object of my invention is to provide for a disk-record phonograph, a variable ratio friction drive of improved construction and of improved operation and dependability; as a feature of my invention in this respect, the friction drive is arranged so that its drive transmission ratio is independent to an unusually high degree of wear or deformation of its friction driving element.

It is another object of my invention to provide improvements in the carriage feeding means which are adapted to insure a positive feed of the carriage at the instant the operation of the machine is resumed following a recoupling of the feeding means, whereby to insure a proper and sufficient spacing between the convolutions of the groove formed on the record at such resumption of the machine operation.

10 Another object is to provide an improved and positively actuated means for effecting a complete and positive engagement of the feed nut and feed screw elements of the carriage feeding means each time these elements are brought into 15 engaging relationship with one another.

It is another object to mount a control head of the machine for travelling movement independent of that of the carriage.

Another object is to provide a drive coupling 20 between the control head and the carriage having a varying drive transmission ratio.

It is a further object of my invention to provide improved indexing means for disk-record phonographs.

25 It is another object to cause the travelling indexing element to move in predetermined relationship to the resultant movement between the record and the record engaging stylus; and, more particularly, it is an object to effect a 30 travelling movement of the indexing element which is substantially in direct proportion to the rate and distance of travel of the record groove past the record engaging stylus.

Another object is to cause a movement of the 35 travelling indexing element which is amplified in relation to the travelling movement between the translating device and the record.

A further object of my invention is to provide, in disk record phonographs, a drive coupling between the travelling indexing element and travelling carriage which has a transmission ratio varying in accordance with the degree of actuation of the coupling.

40 A yet further object is to drive the travelling indexing element through a variable ratio transmission actuated in accordance with the travelling movement between the translating device and record.

50 Other objects and features of my invention lie in the various details of construction and arrangement hereinafter described, and will more fully appear from the following description and the appended claims.

55 In the description of my invention, reference

is had to the accompanying drawings, of which:

Figure 1 is a top plan view of a phonograph constructed in accordance with my invention, some portions being broken away for the better illustration of the interior parts of the phonograph mechanism;

Figure 2 is a vertical sectional view taken substantially along the line 2—2 of Figure 1;

Figure 3 is a partial, vertical sectional view taken through the machine substantially on the line 3—3 of Figure 4;

Figure 4 is a fragmentary top view of the machine illustrating various details in the structural arrangement thereof;

Figure 5 is a vertical section taken substantially along the line 5—5 of Figure 4 and illustrating, in particular, the details in construction of the drive mechanism for the machine;

Figure 6 is a partial, front view of the machine with some parts broken away and other parts appearing in section substantially on the line 6—6 of Figure 1; and

Figure 7 is a fragmentary view taken from the front and illustrating in particular the structural details of a travelling carriage for certain control elements of the machine.

The phonograph herein shown has a frame assembly comprising a pair of left and right end plates 1 and 2 (see Figure 6) which are held together by four tie rods of which there are two upper ones 3 and 4, a bottom one 5 and an intermediate one 6 at the front of the machine, as shown for example in Figure 2. At the ends of the tie rods there are reduced-diameter portions which fit into respective holes in the end plates, and threaded axially into the ends of the rods are screws which clamp the end plates against shoulders on the rods formed by their reduced end portions; for example, on the right end portion of the rod 3 as shown in Figure 4, there is the reduced-diameter portion 3' fitting into a hole 7 in the end plate 2 and there is the headed screw 8 threaded into the end of the rod and clamping the end plate securely against the shoulder 9 on the rod. This frame assembly is housed within a cabinet comprising a bottom plate 12 and a case 13 which fits down over the machine. The cabinet case is rectangular in shape as viewed from the top, and has its bottom plate 12 secured to the frame by screws 14 which thread through the plate into legs 15 projecting down from the end plates 1 and 2. A portion 13a of the front wall of the cabinet is inclined to the rear, along the length of the machine, as shown in Figures 1 and 2.

Supported by the tie rods 3 and 4 at the top of the machine in the right hand portion thereof is a table 20, as shown in Figures 3 and 4. This table is slotted as at 21 and 22, to fit the tie rods 3 and 4, but is held stationary on these rods by means of a set screw 23 which clamps the table to the back tie rod 4. The table serves as a support for a turntable 24 the spindle 25 of which is journaled in the table 20 and supported vertically by a ball thrust bearing 26, as shown in Figure 5.

Overlying the turntable at a small distance thereabove is a flat plate 28. This plate is supported by upward extensions 29 and 30 provided on the table 20 along the front and back thereof, and is held in place on these extensions by screws 31. The edge 28a of the plate along the left side thereof is circular and conforms with the edge of the turntable. This plate projects through an opening 32 in the top wall 13b of the cabinet and

is supported at approximately the same level as this cabinet wall; also, the edge of the opening 32 is shaped generally to conform with the edge of the plate. Thus, the plate and top cabinet wall 5 form a substantially complete cover for the internal parts of the machine.

The plate 28 forms with the top of the turntable a channel which is open along the right side of the machine. This channel is adapted to serve as a guideway for directing a record, which is to be mounted on the machine, into a substantially central position in relation to the turntable. A stopping of the record in the guideway in such position—for example, a position just slightly beyond an exact central position in relation to the turntable—is determined by the abutment of the record against a stop 33 comprising a wall portion extending down from the edge 28a of the plate 28. To facilitate the entry of a record into the guideway a portion 34 along the top of the right wall of the cabinet case 13 is turned in at an upward angle to terminate just at the level of the turntable so as to form a flared mouth for the guideway, as shown in Fig. 6.

Cooperating with the record guiding means just described in the general way described and claimed in Dunning application Serial No. 362,990, filed October 26, 1940, and entitled "Phonographs" 25 as shown in Figures 1, 3 and 5. This device comprises an arm 36 which overlies the plate 28 in a direction extending radially of the turntable. The arm 36—which is preferably formed by die casting—has its rear end portion straddling a post 37 which projects up from the table 20, to which post the arm is pivoted by a pivot rod 38 which passes through ears 39 extending down from the side walls of the arm. Within the arm 36 in the front portion thereof, there is secured a double bracket 40 (see Figures 3 and 4) 30 which is apertured to receive loosely a short spindle 41 having at its lower end a record clamping disk 42. On the upper portion of the spindle 35 within the bracket 40, there is provided a stop collar 43 which serves to retain the clamping disk to the arm 36 by its abutment against the bracket. On the upper end of the spindle there is provided a ball 44 which is adapted to bear against a flat face 45 on the arm to form a thrust bearing for the spindle. Movement of the clamping disk onto the record, by the downward swinging of the arm 36, is permitted by an opening 47 40 in the plate 28 through which the disk may pass.

As the arm 36 is swung down to place the clamping disk on the record a tapered pin 46, 45 which is provided on the bottom of the clamping disk, passes through the central hole of the record and enters a central hole 48 in the turntable to withdraw the record from the stop 34 and to finely center the same in relation to the turntable. The arm 36 is biased down into operated position, to cause the clamping disk to bear against the record, by means of a flat spring 49 which at one end is held by a screw clamp 50 to the plate 28 and at the other end is extended 55 slidably through an aperture 51 in the end wall of the bracket 40. A raising of the arm 36 into unoperated position to lift the disk 42 and pin 46 out of engagement with the record, and a latching of the arm in such unoperated position, is effected by means of a tilt lever 54 pivoted at 55 to the front end of the arm 36. As shown in Figure 3, when the lever 54 is tilted upwardly the inner end thereof will slidably bear upon the plate 28 to raise the arm, and just as the lever

is passed through a dead-center (i. e., vertical) position the downward biasing of the arm 36 will cause the lever to snap ahead into a limiting position determined by the abutment of the lever against an edge 56 on the arm 36. Thus, by a 5 single manipulation of the lever 54, the arm 36 may be both raised into unoperated position and then latched in this position.

It will be seen that the record guiding and clamping means just described renders the 10 mounting of a record on the machine a very simple operation. For instance, it involves only inserting the record into the guideway and sliding it over the turntable until it abuts against the stop 34 and then tripping the lever 54 to release the latch on the arm 36. The removal of the record from the machine is equally as simple as it involves only performing a single manipulation on the lever 54, to raise and latch the arm 20 36 in unoperated position, and then gripping the record at the mouth of the guideway and sliding it off from the turntable.

Movably mounted on the tie rods 3 and 4 to the left of the table 20 is a carriage 60 having at its rearward end a slotted portion 61 which slidably fits the tie rod 4 and having at its forward end two spaced bearings 62 and 63 which slidably embrace the tie rod 3, as shown in Figures 2, 4 and 6. This carriage, like the table 20, is provided at its front and back with upward 30 extensions 64 and 65 (see Figure 2) which project above the top wall 13b of the cabinet case through slot-like extensions 66 of the opening 32 in the top cabinet wall. Bridging the extensions 64 and 65 and connected thereto by screws 67 is a rectangular frame 68, as shown in Figure 1. This frame serves as the support for a recording and reproducing translating means which by way of example is illustrated as comprising separate recording and reproducing units 69 and 70. These two units are carried respectively in the front half and back half portions of the frame. The units are pivoted at their far ends, for up and down freedom of movement in relation to a mounted record, by means of horizontally disposed cone pivots 71 which thread through the left and right sides of the frame into engagement with the frame structures of the units. In the case of the reproducing unit 70 the cone pivots 71 do not directly pivotally engage the unit itself but instead engage the ends of a block 72 which is connected by a vertical pivot 73 to a tail-piece 74 on the unit 70. This vertical pivot is provided to afford a lateral freedom of movement to the reproducing unit 70 in order to permit the unit to freely track the groove on the record.

The translating units 69 and 70 are herein only diagrammatically shown as they may be of any suitable type, and need not be described other than that they are respectively provided at their free end portions with recording and reproducing styli 69' and 70' which project down below the units. When the translating units are lowered their respective styli pass through an opening 75 in the plate 28 into engagement with the record, the weight of the units themselves being relied upon to effect a proper coaction between the record and the styli.

A travelling movement of the carriage 60 along the rods 3 and 4, to cause the translating units to traverse the record, is effected by means of a feed screw 80 and cooperating feed nut 81, as shown in Figure 6. The feed nut 81 is carried by a bail member 82 which is pivoted on a cross rod 83. This rod is supported at its ends by

the end plate 1 and by a standard 84 of the table 20; the rod is biased longitudinally by a spring 167 against a ball thrust bearing 84' in the standard 84, but is permitted to pivot about its longitudinal axis as is hereinafter explained. The feed screw 80, which is in the form of a threaded sleeve, slidably embraces a shaft 85 that is journaled in standards 86 and 87 projecting down from the carriage 60. These standards 25 abut against the ends of the screw and thus hold the feed screw stationary against longitudinal movements in relation to the carriage. The feed screw is rotated by way of the shaft 85 to which it has a spline connection formed by a set screw 88 that threads through the feed screw into engagement with a slot 89 provided in the shaft 85 longitudinally thereof.

Driving torque of the feed screw is obtained from the turntable 24 through a drive transmission which comprises a pinion 92 on the turntable spindle 25, a gear 93 in mesh with the pinion and having a vertical shaft 94 journaled in the table 20, a pair of bevel gears 95 connecting the shaft 94 to a horizontal shaft 96 journaled in the standard 84 at a point axially in line with the shaft 85, and a flexible shafting 97 interconnecting the shafts 85 and 96. The reason for using a shafting 97 of the flexible type is to overcome the need for a critical aligning of the shafts 85 and 96.

The friction drive for the turntable—which is shown in Figures 2, 3, 4, 5 and 6—comprises a drive cylinder or sleeve 100 having end portions 101 of reduced bore which bear rotatably on a rod 102 extending centrally through the sleeve. The rod is supported by the end plate 1 at its left end and by the table 20 at its other end, and is held in a position wherein the sleeve 100 lies below the level of the turntable and in a direction extending radially thereof. This drive sleeve is rotated by a motor M which has belt connection 103 with a pulley 104 on the sleeve at its left end. Driving torque from the sleeve 100 to the turntable 24 is transmitted by way of a friction wheel 105 interposed between the drive sleeve and the turntable and supported by the carriage 60. This wheel has a drive surface 105' suitably of a yieldable material such as rubber which frictionally engages the drive sleeve at its bottom and the lower turntable face at its top, each at points substantially directly below the styli 69' and 70' of the translating units. In the travelling movement of the carriage 60 the friction wheel is fed along the drive sleeve and radially along the face of the turntable. As the carriage is moved to the left—the friction wheel being then moved away from the center of the turntable—the rotational speed of the turntable is gradually decreased; the linear speed of the turntable past the friction wheel will however remain at a constant value; likewise, the movement of the record groove along the engaging stylus of the translating unit, since the latter is positioned directly above the friction wheel and carried therewith, will also be constant and of the same value.

The friction wheel 105 as here employed comprises an intermediate coupling member of the friction drive. As so used, the wear on the drive surface of the wheel, and any deformations or "flats" which may develop thereon from leaving the friction wheel pressed against its cooperating members during long periods of idleness of the machine, tend to be the same at both engaged 70 75 surfaces of the friction wheel at each position

of the wheel in its rotation. Thus, the ratio of the radii of the wheel at its engaged points tending to remain constant, the drive transmission ratio through the friction wheel remains substantially constant throughout each turn of the wheel during the period of its use.

In order that friction driving pressure of the drive sleeve 100 against the friction wheel 105 may be relieved at will, to unclutch the friction drive, the rod 102 on which the drive sleeve is journaled is movably supported to permit a limited up and down freedom of movement of the drive sleeve. To provide this freedom of movement the left end of the rod 102 is pivotally supported by fitting the same loosely into the bore of a collar 108, pivoting the rod to the collar by means of a cross pin 109, and staking the collar to the end plate 1, as shown in Figure 5. The right end of the rod 102 is then movably supported by journaling a ball head 110 on the end of the rod into the horizontal arm 111a of a clutch lever 111 and pivoting this lever, as at 112, to the left end wall of the table 20. (See Figures 3 and 5). This clutch lever is biased by a tension spring 113 (see Figure 3) so as to provide a normal driving pressure between the drive wheel and friction coupling. This driving pressure may however be relieved, at will, merely by rocking the clutch lever 111 in a counterclockwise direction.

The friction wheel 105 is mounted on the carriage and provided with a vertical freedom of movement in order that it may equalize itself between the turntable and drive sleeve. The mounting for the friction wheel comprises a bracket 115 which is screwed to the right end wall of the carriage and turned to the left over the carriage. Turned down from the sides of the bracket are ears 117 which project into a clearing slot 118 provided in the carriage beneath the bracket. Pivoted to these ears on a pivot pin 119 is a short rod 120 which extends horizontally along the slot 118 and through an enlarged hole 121 in the end wall of the bracket, and journaled on the end portion of this rod beyond the bracket is the friction wheel 105.

It will be seen from the structure so far described that when the feed nut 81 is retained in engagement with the feed screw 80 and the clutch lever 111 is placed under the influence of its biasing spring 113 to effect a normal driving pressure of the drive sleeve against the friction wheel and of the friction wheel against the turntable, then the driving torque from motor M will be applied to the turntable 24 and through the turntable to the feed screw 80 both to rotate the turntable and effect a leftward feed or travel of the carriage 60 along the rods 3 and 4. This travel of the carriage causes the translating units to traverse the top of the turntable away from the center thereof, the friction wheel 105 similarly to traverse the bottom of the turntable, and the shaft 85 to move lengthwise through its bearings and through the feed screw 80. As the friction wheel engages the turntable at larger radial distances from the center of the turntable, the rotational speed of the turntable progressively decreases (whereby to maintain a constant linear speed of the record groove past the styli as hereinbefore explained) but so also decreases in the same degree the travelling speed of the carriage 60; thus, the styli of the translating units are moved relative to the record along a spiral line of constant pitch—i. e., of equal radial displacement between each convolution and the next.

The recording and reproducing translating units 69 and 70 are placeable into and out of operative condition—the condition wherein their styli operatively engage the record—merely by lowering and raising the units onto and from the record. The conditioning of these units is effected by means of a slide 125 which is mounted on the left side of the frame 68 through pin and slot connections 126 (see Figures 1, 2 and 6). 5

Provided on the top edge of the plate is a raised cam 127 having a central dwell 127a, and extending over the slide 125 from the free end portions of the translating units 69 and 70 are lift tabs 128 and 129 respectively. When the slide 125 is in a forward position the cam 127 is ahead of the lift tab 129 of the reproducing unit to render this unit free to engage the record in response to its own weight, but the dwell 127a of the cam is in contact with the lift tab 128 of the recording unit to retain this unit in a raised or inoperative position; as the slide is moved rearwardly into a central position the tab 129 rides up onto the dwell of the cam and the tab 128 remains yet on this dwell to cause both units to be retained in inoperative position; and as the slide is further moved into its rearward position the tab 128 rides off from the cam to permit the recording unit to engage the record in response to its own weight but the tab 129 remains on the dwell of the cam to retain the reproducing unit in inoperative position. Obviously, when the slide is moved forwardly this sequence of events will be reversed.

The selective conditioning of the translating units and the engaging and disengaging both of the carriage-feeding means and of the drive clutch, are all controlled concurrently by a single control lever 135. This lever projects through an opening 135' in the front of the cabinet case 4 and extends across the inclined cabinet wall portion 13a, as shown in Figure 2. The lever is mounted for travelling movement along the front of the machine, and carried with this lever is an indexing device 136, hereinafter described, which with the control lever 135 forms a so-called control head for the machine. The mounting for this control head, which is shown in Figures 1, 3, 4 and 7, comprises a cross rod 10 supported at its ends by the end plates 1 and 2 and a bracket-shaped member 137 having apertured left and right legs 137a and 137b which embrace the end portions of a sleeve 138 that slides freely upon the cross rod 10. The aperture in the left leg 137a of the member 137 has a reduced bore to fit a reduced diameter end portion 138a of the sleeve (see Fig. 7), and on the outer side of the right leg 137b of the member 137 there is screwed a plate 139 which bears against the end of the sleeve and holds the latter from longitudinal movement in relation to the member 137. The plate 139 is of an irregular contour, having an upward extension 139a serving as a support for the indexing device 136, as is hereinafter described, and further having a forward extension 139b which straddles the front tie rod 6 to hold the bracket member 137 from turning on the rod 10. The control lever 135 is provided with a hub 135a which embraces the sleeve 138. The control lever is permitted to pivot on the sleeve 138 but is held stationary against movement therewith by means of a set screw 140 threaded through the hub 135a into a transverse slot 141 in the sleeve, as shown in Figure 7. A spline connection of the control lever to the rod 10 is effected by providing a slot 142 in the rod 10.

longitudinally thereof and extending the set screw 148 into engagement with this slot, the set screw being however slideable along the slot so as not to restrict the travelling movement of the control head along the rods 10 and 6.

The separate elements controlled by the control lever 135 have a common coupling to the lever through the medium of the rod 10 and, because of this coupling function of the rod, the same is splined to the control lever, as above described. For the same reason, the rod is pivoted at its ends in the end plates 1 and 2 through the provision of reduced diameter portions at the ends of the rod which are fitted in holes in the end plates, there being, for example, the reduced portion 10' at the right end of the rod which fits into the hole 11 in the end plate 2 as shown in Figure 4. The means by which the rod is coupled to the slide 125 to control the condition of the translating units 69 and 70, and to the lever 111 to control the drive clutch, comprises a bail 144 which, as shown in Figure 1, has its left end portion pivoted, as at 145, into the end plate 1 and its right end portion terminating into the aforementioned rod 38 which forms the pivot for the arm 36 on the post 37. The bail 144 is rocked on its pivots by a turning of the rod 10 through the medium of a link 146 (see Figure 2) pivoted at its rear end to the bail and at its forward end, as at 147, to a plate 148 secured to the left end portion of the rod 10. The coupling of the bail 144 to the slide 125, which is shown in Figure 2, comprises a rock lever 149 pivoted centrally thereof, as at 150, to the extension 65 of the carriage 60. The lower end of the rock lever straddles the bail at 151, and is permitted to slide therealong in the travel of the carriage, while the upper end of the lever is pivoted at 152 to the slide 125. The coupling of the bail to the clutch lever 111, which is shown in Figure 3, comprises a slide 153 mounted through screw and slot connections 154 on the left side of the table 20. At its rearward end the slide has a vertical slot 155 through which passes the bail 144, and at its forward end the slide has a downwardly extending V-shaped cam 155 which cooperates with a similarly shaped but upwardly extending cam 156 on the arm 111a to control the clutch lever 111.

In considering the control functions of the control lever 135, as so far described, it will be seen that when the control lever is in a central or inoperative position—the position occupied by the lever in Figures 2 and 3—the slides 125 and 153 occupy their central positions and, as a result, the translating units 69 and 70 are retained in their inoperative positions and the drive sleeve 100 is retained in a lowered position to hold the drive clutch disengaged. However, when the control lever 135 is swung into an upward or reproducing position the slide 125 is moved forwardly to place the reproducing unit 70 into operative position (while retaining the recording unit in inoperative position) and the slide 153 is moved rearwardly to free the cams 155 and 156 from one another and thus permit an engagement of the drive clutch in response to the action of the spring 113; and when the control lever is swung into a downward or recording position the slides 125 and 153 are moved in the reverse directions from the foregoing to place the recording unit into engagement with the record (while retaining the reproducing unit in inoperative position) and again to permit the spring 113 to engage the drive clutch. In order that the respective positions of the control lever may be clearly defined there is

5 pivoted on a stud 210, carried by the plate 139, a detent 211 which is biased by a tension spring 212 into engagement with a notched extension 213 on the hub of the control lever, as shown in Figures 3 and 7.

The action of the control lever 135 on the carriage feeding means is such as to place the feed nut 81 out of engagement with the feed screw 80 when the lever is in inoperative position and into engagement with the feed screw when the lever is in either its recording or reproducing positions. The means by which this is accomplished comprises an upward cam extension 160 on the plate 148 and a cooperating pin 161 on an arm 162 of the bracket 82. When the control lever is in inoperative position the tip of the cam extension 160 engages the pin 161 to hold the bracket in a counter-clockwise direction (as it appears in Figure 2) and the feed nut out of engagement with the feed screw; but when the control lever is swung into either recording or reproducing positions the cam extension moves free from the pin, in either one direction or the other, and the bracket 82 is then swung in a clockwise direction on the rod 83 by a tension spring 163 connected between the arm 162 and a pin on the end plate 1.

It is highly important to a proper operation of the phonograph—particularly in the course of recording—that the threads of the feed nut and feed screw come into positive and complete engagement each time the control lever 135 is manipulated to place the machine into recording condition. If it fails to do this a "slack" is left between the threads of the nut and screw, of some length up to the spacing between successive convolutions of the thread, and the initial period of operation following the manipulation of the control lever will be consumed in taking up this slack without incurring any actual feeding of the carriage; this loss in carriage feed causes the groove convolutions formed on the record by the recording stylus to be crowded together and even to overrun one another. To insure against such possible crowding or overrunning of the groove convolutions, through an incomplete engagement of the threads of the feed nut and feed screw, I provide means by which a positive advance of the feed nut along the feed screw, through approximately the distance of spacing between succeeding thread convolutions, is effected each time the machine is shifted from neutral to recording condition. This feed-nut advance means is actuated positively by the manipulation of the control lever 135 into recording position, but the actuation is timed to occur only as a terminal result of this manipulation in order that the advance of the nut will not take place before it has engaged the screw.

This feed nut advance means is shown in Figures 2 and 6 and comprises the following principal elements: An arm 165 pinned to the rod 83 between the legs of the feed-nut supporting bracket 82; a cam face 165' on the left side of the hub of the arm 165; a cross pin 166 on the left leg of the bracket 82 which engages the cam face 165'; and the aforementioned compression spring 167 which is mounted on the rod 83 between the end plate 1 and the bracket 82 and which biases the bracket to the right along the rod 83 into a position determined by the abutment of the pin 166 against the cam face 165'. As the control lever 135 is swung down into recording position, the cam face 169 on plate 148 impinges against the pin 168 to rock the arm 165 in a clockwise direction. As the rod is so rocked the

bracket 82, by the action of cam face 165' against pin 166, is pushed a short distance along rod 83 towards plate 1 against the pressure of the spring 167. The feed nut is thus moved positively to the left as a terminal result of each placement of the control lever 135 into recording position. When the control lever is returned to inoperative position the arm 165 is returned to unoperated position by a tension spring 170 and the feed nut advance means is thus conditioned for re-operation by the action of spring 167.

In order that the record rotation may be stopped at will without disturbing any other adjustment of the machine—for example, to give the operator time to determine the course of his thoughts during a dictation recording operation—there is provided an independent mechanism for actuating the drive clutch. This actuating mechanism, which is herein diagrammatically shown (see Figure 3) and referred to as 171, may be of any suitable type—for example, an electromagnetic device such as that disclosed in Langley Patent No. 1,380,486, issued June 7, 1921, and entitled "Controlling device." A device of this type has an electromagnetically actuatable armature 172 from which the power to operate the drive clutch is taken by way of a link 173 pivoted to the armature as at 172'. The far end of this link has a pin and slot, or lost motion, connection 174 with a downwardly extending arm 11b of the clutch lever 111; this connection 174 is made of the lost-motion type in order that the clutch lever 111 may be operated by the control lever 135 to control the drive clutch as heretofore described without producing any actuation of the mechanism 171.

In the inclined front wall portion 13a of the cabinet case, along the greater part of the length of the case, there is provided a rectangular opening 175, which is a downward continuation of the aforementioned opening 135' through which extends the control lever 135; and supported in the plane of the inclined wall portion 13a in the opening 175 is a holder 176 for an index slip, as is shown in Figures 1, 2 and 3. This holder is of the usual type, comprising a flat plate 176a having its top and bottom edges 176b turned over to form a channel through which an index slip 177, made for example of paper, may be inserted from the right end of the holder and be retained therein. The support for this holder comprises a bracket 178 secured by screws 179 to the rod 6 and secured as by welding to the holder 176.

Marks or annotations of an explanatory character as with respect to selected portions of recorded matter are made by the indexing device 138 hereinbefore referred to. This indexing device is herein illustrated, purely by way of example, as of the type disclosed in Gramman Patent No. 2,184,914, issued December 26, 1939, and entitled "Phonograph," and to which reference may be had for a description of the same in all its details. This type of indexing device forms the annotations by perforating or punching the index slip. These perforations are effected by means of keys of which in the present instance there are two referred to as 180 and 181 and designated respectively by the letters L and C, the key marked L being for purposes of denoting length of individual sequences of recorded matter and the key marked C being for the purpose of denoting points where corrections have been made in the recorded matter. These keys are carried by the upper one of a pair of jaws 182 and 183 which project forwardly from the afore-

mentioned plate extension 139a, one over the top and one below the bottom of the index holder 176. Extending through these jaws are holes 184 and fitted into these holes are punching members 185 secured to the keys. In line with each key, in the bottom of the index holder and along the length thereof, is a slot 186, and associated with the keys are springs (not shown) which resiliently hold the keys in raised positions. As the keys are depressed the members 185 punch through the slips and pass through the slots 186 in the bottom of the holder to enter the holes 184 in the lower jaw 183. The punchings from the slips are collected by a trough 187 formed below the jaw 183 from an extension of the bracket 178.

In the usual phonograph arrangement the indexing device is mounted directly on the carriage of the machine to partake of its movement across the index slip holder, or of the travelling movement of the translating device across the record. In a disk-record phonograph the travelling movement of the translating device is small and in a uniform groove speed type of disk-record phonograph the amount of recorded matter on the record which is represented by a given radial displacement of the device in its path varies continuously throughout the movement of the device. It is thus desirable in this type of phonograph that the movement of the indexing device be to an amplified scale in relation to the travelling movement between the translating device and the record and also that it be so proportioned in relation to the movement between the record and engaging stylus that a given displacement of the indexing device from any point in its path will represent a fixed amount of recorded area on the record. To achieve these objectives the indexing device is provided with a movable mounting which is independent from that of the carriage—the indexing device being slidably mounted on the rods 6 and 10 with the control lever 135 as hereinbefore described—and is connected to the carriage through a drive coupling having an amplified and varying movement-transmitting ratio. The varying transmitting ratio of this drive coupling is controlled so that the rate of travelling movement of the indexing device is maintained at all times substantially in direct proportion to the linear speed of the resultant movement between the record and the translating units; or, expressed in other words, the drive coupling is arranged to effect a displacement of the indexing device along the index slip holder which is in direct proportion to the length of record groove traversed by the engaging stylus.

To effect a movement of the indexing device in the manner just described there is provided a gear rack 190 on a frame 191 which is secured by screws 192 to the top of the end plate 1, the frame being thus held in a horizontal plane at a small distance below the top of the machine, as shown in Figures 1, 2 and 6. Journalled in the carriage 60, as at 193, (see Figure 4) is a pinion 194 which meshes with the rack 190 and which carries a grooved pulley 195 having a portion of its periphery in a form of a spiral. At the tip 195' of the drive pulley 195 (see Figure 1) there is fastened, by a clamping screw 196, one end of a flexible cord 197 which is wrapped about the drive pulley in a clockwise direction to the most rightward point of the pulley. From this point the cord runs off from the drive pulley in a forward direction, forms a loop along the front,

right and back sides of the machine and then returns to the drive pulley at the same point at which it left the pulley. This loop of the cord is directed by a series of rollers around which the cord passes, there being for this purpose two pairs of rollers 198 and 199 pivoted on the frame 181 at its front and back respectively, and two rollers 200 and 201 pivoted on the table 20 at the front and back right hand corners of the machine. The return end portion of the cord is wrapped about the drive pulley 195 nearly to the point of fastening of the start end of the cord, and is there secured to the drive pulley by an anchor nut 202, which nut serves also as a means for tightening the cord to the desired degree of tautness. This cord is connected to the movable control head of the machine by a screw clamp 203 which clamps the cord tightly to a bracket 204 provided on the upward extension 199a of the plate 199, as shown in Figures 2, 3 and 4.

The pitch of the pulley 195—i. e., the change in radius per unit angular change—is the prime factor determining the transmission ratio of the drive coupling between the control head and the carriage 60 and may be ascertained from the following mathematical considerations:

If we write θ for the rotational speed of the turntable 24 and r for the driving radius of the turntable, or distance from the center of the turntable to the friction coupling wheel 105 (the distance also of the center of the turntable to the engaging stylus) then,

(1) $r\theta=k$, a constant, for a constant linear speed of the record groove past the stylus

If we let d stand for the rate of travel of the carriage, then

(2) $d=k_1\theta$ where k_1 is another constant determined by the drive connection between the turntable and the carriage feed

Substituting Eq. 1 in Eq. 2

$$(3) \quad d=k_1k/r$$

If we let θ_p stand for the rate of turning of the drive pulley 195, then

(4) $\theta_p=k_2d$ where k_2 is a constant depending upon the radius of the pinion 194

Substituting the value of d of Eq. 3 into Eq. 4

$$(5) \quad \theta_p=k_2k_1k/r$$

If we let r_p stand for the radius of the drive pulley 195 at its point of drive (i. e., at the point where the cord runs off from the pulley) and t stand for the rate of travel of the cord, then

$$(6) \quad t=\theta_p r_p,$$

And substituting Eq. 5 in Eq. 6

$$(7) \quad t=kk_1k_2r_p/r$$

From Eq. 7 it is clear that the rate of travel of the cord, and thus also of the control head or indexing device across the index slip holder, may be amplified in relation to the carriage travel according to the value chosen for the drive constant k ; and that it will be constant in value—the same as the rate of travel of the record groove past the stylus—so long as the radius r_p at the drive point of the pulley 195 is maintained at a fixed ratio in relation to the driving radius r of the turntable. It is on the basis of fulfilling this fixed proportionality between r and r_p that the pitch of the drive pulley is determined.

In further considering the drive coupling between the control head and the carriage 60 in terms of Eq. 7, it will be seen that the variable radius r_p of the pulley 195 determining the variable drive transmission ratio of the drive coupling should be maintained in fixed proportion to the displacement of the carriage along its path. Since the actuation or angular displacement of the drive pulley is in direct proportion to the carriage displacement, it follows then that the drive radius of the pulley 195 should vary according to the degree of its actuation.

If the proportionality between the drive radius r_p of the spiral pulley 195 and the drive radius r of the turntable 24 is made unity in value, then the change in radius at the point where the cord leaves the spiral pulley is exactly equal to the distance of travel of the carriage. Thus when the spiral pulley is mounted on the carriage, as has been heretofore described, the change in radius at the drive point of the pulley is exactly compensated by the carriage travel and, as a result, the drive point on the pulley remains fixed or stationary in relation to the frame of the machine; this is a highly desirable result as it permits the driving movement to be taken from and transmitted to the drive pulley 195 without error or mechanical difficulty.

Although I have herein shown and described my invention in terms of a particular embodiment it will be understood that this embodiment is illustrative but not limitative of my invention as the same is subject to many changes and modifications without departure from the scope of my invention, which I endeavor to express according to the following claims.

I claim:

1. In a phonograph including a rotatable support for a disk record, a record-cooperating translating device and means to effect a relative travelling movement between said device and said support: the combination of an indexing means for the phonograph comprising two parts arranged for relative travelling movement; and a movement transmission operatively connecting said indexing means with said movement-effecting means and having a varying movement-transmitting ratio causing the rate of travelling movement between said two indexing parts to vary in relation to that of the travelling movement between said support and translating device.

2. In a phonograph including a rotatable support for a disk record, a record-cooperating translating device and means to effect a relative travelling movement between said device and said support: the combination of indexing means for the phonograph having a movable indexing element; and a drive connection between said movement-effecting means and said indexing element including means causing the movement-transmitting ratio of the drive connection to vary progressively in predetermined relation to the distance of travel between said translating device and said support.

3. In a phonograph having a record supporting device and a translating device, one of said devices being mounted for travelling movement in relation to the other: the combination of an indexing means for the phonograph comprising a movable indexing element; and movement-transmitting means between said element and said one device having a movement-transmitting ratio of different magnitude at different relative positionings

between the translating device and record supporting device.

4. In a phonograph having a record supporting device, a translating device and means mounting one of said devices for travelling movement in relation to the other: the combination of an indexing means having an element arranged for travelling movement; and a movement transmission between said indexing element and said one movable device including means actuated by said one movable device in accordance with the travel of the same for varying the movement-transmitting ratio of said transmission.

5. In a phonograph having a record supporting device, a translating device, and means mounting one of said devices for travelling movement in relation to the other: the combination of an indexing means having an element arranged for travelling movement; and a movement transmission between said indexing element and said one movable device including means to cause a varying amplified movement of said indexing element in relation to the movement of the said one movable device.

6. In a disk-record phonograph having a turntable and a translating device, one of said two mentioned elements being mounted for travelling movement whereby to permit a traverse of the translating device in relation to the turntable substantially along a radial line of the latter: the combination of an indexing means for the phonograph having a part arranged for travelling movement; and a drive coupling between said part and the movable one of said first two mentioned elements including a variable ratio movement-transmitting means actuated by said one movable element in the travel of the same to cause the movement-transmitting ratio of said drive coupling to vary in direct proportion to the radial displacement of said translating device from the center of said turntable.

7. In a phonograph comprising a turntable, a translating device, and drive means for rotating said turntable and concurrently effecting a travelling movement between the turntable and said device whereby to cause a resultant movement of constant velocity between the turntable and translating device: the combination of indexing means for the phonograph having an indexing element arranged for travelling movement; and a variable ratio movement-transmitting means actuated by said drive means and controlled in predetermined relation to the travelling displacement between said device and said support, for causing a travelling movement of said indexing element at a rate bearing a fixed proportional relationship to the velocity of the resultant movement between the turntable and translating device.

8. In a phonograph having a record support and a translating device, one of said two elements being mounted for travelling movement in relation to the other: the combination of indexing means for the phonograph having an element arranged for travelling movement; a spiral member rotated by said one movable element in response to the travelling movement of the same; and means transmitting to said indexing element the movement of the periphery of said spiral member past a fixed radial line thereof.

9. In a phonograph having a record support

and a translating device, one of said two elements being mounted for travelling movement in relation to the other: the combination of indexing means for the phonograph having an element arranged for travelling movement; a pivotal spiral member carried with said one movable element; means causing a pivotal movement of said spiral member at a rate proportional to that of the travelling movement of the same, the pitch of said spiral member being such that the radius of the spiral member in the line of its travel varies in direct proportion to the distance of travel of the member whereby to cause the periphery of the spiral member at said line to remain stationary in relation thereto; and means for imparting to said indexing element the transverse movement of the periphery of said spiral member past said line of travel.

10. In a phonograph having a record supporting device, a translating device and means mounting one of said devices for travelling movement relative to the other: the combination of a control head for the phonograph; means mounting said control head for travelling movement relative to that of the movable one of said devices; and variable ratio movement-transmitting means coupling said one movable device with said control head for causing a travelling movement of one in predetermined relationship to that of the other.

11. In a phonograph having a record supporting device, a record-cooperating translating device, one of said devices being mounted for travelling movement relative to the other: the combination of means associated with said device for adjusting the same into operative and inoperative conditions in relation to a supported record; a manipulatable control member for said adjusting means operatively connected thereto and mounted to travel independently of the movable one of said devices; and movement-transmitting means coupling the movable one of said devices with said manipulatable member for causing a travelling movement of one in response to a travelling movement of the other.

12. In a phonograph including a record-supporting device, a translating device and means for effecting a relative travelling movement between said devices: the combination of an indexing means having an element arranged for travelling movement; and a movement transmission between said movement-effecting means and said element having a movement-transmitting ratio greater than unity and varying in predetermined relation to the relative displacements between said translating and record-supporting devices.

13. In a phonograph including a supporting device for a disk record and a translating device, one of said devices being mounted for travelling movement whereby to produce a traversing movement of the translating device relative to the face of a supported record: the combination of indexing means including a movable indexing element; and means, actuated to a degree varying in accordance with the amount of displacement between said devices, for causing said indexing element to be displaced in varying amplified relation to the said displacement between the devices.

CHARLES W. DANN.
